Primary Examiner — Christian P. McLean*Assistant Examiner* — Kristopher Michael Blechschmidt(74) Attorney, Agent, or Firm — Taft Stettinius & Hollister LLP(57) CLAIM

The ornamental design for a keyboard neck fishing net, as shown and described.

DESCRIPTION

FIG. 1 is a side view of a keyboard neck fishing net showing my new design;

FIG. 2 is a front view thereof;

FIG. 3 is a rear view thereof; and,

FIG. 4 is a perspective view thereof.

The broken lines illustrate portions of the keyboard neck fishing net that form no part of the claimed design.
